TRACY R. CAMPBELL, OF OUTREMONT, QUEBEC, CANADA, ASSIGNOR TO WESTERN ELECTRIC COMPANY, INCORPORATED, OF NEW YORK, N. Y., A CORPORATION OF NEW YORK

INSULATOR MOUNTING

Application filed December 8, 1927, Serial No. 238,547, and in Canada August 20, 1927.

This invention relates to insulator mountings.

Its object is to provide a simple and inexpensive mounting, which will be strong, 5 secure and durable.

In accordance with this invention the insulator is provided with a recess in its lower face, and is secured to the cross-arm by a key having lugs which engage the under face of 10 the cross-arm, and a part which passes through the cross-arm into said recess, the recess being subsequently filled with cementitious material to anchor the key in place.

Referring to the drawings,

Fig. 1 is a central vertical section through a portion of an insulator mounted in accordance with my invention, the section being taken on the line 1—1 of Fig. 2.

Fig. 2 is a section on the line 2—2 of Fig. 1.

Fig. 3 is a perspective view of a portion of an insulator supporting bar or cross-arm fashioned in accordance with my invention.

Fig. 4 is a perspective view of a substantially U-shaped key used in my invention.

Fig. 5 is a similar view of a modified form of key.

Fig. 6 is a central vertical section of a portion of an insulator in the process of being mounted, using the modified form of key shown in Fig. 5.

Fig. 7 is a section of the completely mounted insulator using the modified key of Fig. 5, the section being taken similarly to Fig. 6.

Fig. 8 is a plan view of a portion of an insulator supporting bar having an I-shaped cut therein, preparatory to forming the structure as shown in Fig. 3.

In the drawings like characters of reference indicate corresponding parts in the various views.

In carrying out my invention the insulator 3 is provided with an axial recess 4 in the base end thereof which orifice is of rectangular cross-section and the walls of which are inclined outwardly from the mouth to the bottom of the recess so that the recess is wider, as it were, at the bottom than at the mouth.

An insulator supporting bar or cross-arm 5 is used and is in the form of a metal bar.

The form of my invention illustrated in Figs. 1—2—3—4 and 8 will first be described.

The supporting bar 5 is first cut with an I-shaped cut 6 (see Fig. 8) which forms two flaps 7.

These flaps 7 are then turned upwardly (see Fig. 3) which operation forms a rectangular orifice 8 in the bar 5 and the flaps 7 constitute flanges upstanding from two opposite marginal edges of this orifice.

A substantially U-shaped key 9 (see Fig. 4) is employed and this key is formed with lugs 10 extending from the extremities of the arms of the key.

In mounting an insulator according to the form of my invention illustrated in Figs. 1—2—3—4 and 8, the insulator 3 is placed upon the bar 5 so that the orifice 8 in the bar registers with the recess 4 and the upstanding flanges 7 project into the recess 4, (see Fig. 1).

The key 9 is then inserted through the orifice 8 and into the recess 4 in the insulator, which recess it only partially fills.

When in its inserted position (see Fig. 1) the lugs 10 of the key engage against the face of the bar 5 remote from the insulator.

The recess 4 is now filled with any suitable cementitious material 11 such as lead or cement, so as to completely fill the remainder of the recess 4 and the portion of the key 9 within the recess is completely imbedded therein so that, when the substance 11 hardens, the key 9 is permanently anchored within the recess 4, and, since the lugs 10 thereof are engaged against the opposite face of the bar 5, the insulator 3 is very firmly mounted upon the bar 5.

By making the walls of the recess 4 taper outwardly from the mouth to the bottom, the strength of the mounting is greatly increased upon hardening of the cementitious substance 11.

The form illustrated in Figs. 5, 6 and 7 is slightly modified in that a slightly different form of key 12 is used and the upstanding flanges 7 are omitted, the insulator supporting bar 13 being simply formed with a rectangular orifice 14 which registers with the recess 4 in the insulator 3.

In this form, the key 12 is very much the same as the key 9 previously described in that it is substantially U-shaped and is formed with similar lugs 10.

The central branch of the key however is deformed at 15.

In using this mounting, the insulator 3 is placed upon the bar 13 so that the orifice 14 in the bar registers with the recess 3 in the insulator.

10 The key 12 is then inserted through the orifice 14 in the bar 13 and into the recess 3 so that the lugs 10 engage against the face of the bar 13 remote from the insulator in the same manner as previously explained.

15 The relative positions of the parts are now as shown in Fig. 6.

20 The deformation 15 in the key is now straightened out by any suitable tool so that the key assumes the form shown in Fig. 7, in which the base of the key is expanded so as to wedge the sides of the key against the walls of the recess 4.

25 Cement 16 is then placed within the recess and when it hardens the key will be held in its expanded form so as to be permanently anchored within the recess and since the lugs 10 are engaged against the face of the bar 13 the insulator will be securely mounted upon 30 the bar 13.

35 From the foregoing it will be evident that my invention provides a very simple and inexpensive mounting for insulators whereby the objects of my invention have been attained.

40 Various modifications may be made in my invention without departing from the spirit thereof or the scope of the claims and therefore, the exact forms shown are to be taken 45 as illustrative only and not in a limiting sense and I desire, that only such limitations shall be placed thereon as are imposed by the prior art or are specifically set forth in the appended claims.

45 What is claimed is:

1. In an insulator mounting, in combination, an insulator having a recess in the end thereof, an insulator supporting bar against which the recessed end of the insulator rests, 50 said bar having an orifice therein registering with the recess in the insulator, a substantially U-shaped key, lugs extending from the extremities of the arms of the key, the key extending freely through the orifice in the 55 bar and into the recess in the insulator, the aforesaid lugs on the key engaging the face of the bar remote from the insulator, and means for permanently securing the key within the recess.

60 2. In an insulator mounting, in combination, an insulator having a recess in the end thereof, an insulator supporting bar against which the recessed end of the insulator rests, 65 said bar having an orifice therein registering with the recess in the insulator, a substantial-

ly U-shaped key, lugs extending from the extremities of the arms of the key, the key extending freely through the orifice in the bar and into the recess in the insulator, and partially filling said recess, the aforesaid lugs on the key engaging the face of the bar remote from the insulator, and cementitious material introduced into said recess subsequently to the insertion of the key thereinto and filling the remainder of the recess to permanently anchor the key therein.

70 3. In an insulator mounting, in combination, an insulator having a recess of rectangular cross-section in the end thereof, an insulator supporting bar against which the recessed end of the insulator rests, said bar having a rectangular orifice therein registering with the recess in the insulator, flanges upstanding from opposite marginal edges of the orifice in the bar and extending into said recess in the insulator, and cementitious material filling the recess and permanently anchoring the aforesaid flanges therein.

75 4. In an insulator mounting, in combination, an insulator having a recess of rectangular cross-section in the end thereof, the walls of said recess inclined outwardly from the mouth to the bottom thereof, an insulator supporting bar against which the recessed end of the insulator rests, said bar having a rectangular orifice therein registering with the recess in the insulator, flanges upstanding from opposite marginal edges of the orifice in the bar and extending into said recess in the insulator, and cementitious material filling the recess and permanently anchoring the aforesaid flanges therein.

80 5. In an insulator mounting, in combination, an insulator having a recess of rectangular cross-section in the end thereof, an insulator supporting bar against which the recessed end of the insulator rests, said bar having a rectangular orifice therein registering with the recess in the insulator, flanges upstanding from opposite marginal edges of the orifice in the bar and extending into said recess in the insulator, a substantially U-shaped key, lugs extending from the extremities of the arms of the key, the key extending freely through the orifice in the bar and into the recess in the insulator and partially filling said recess, the aforesaid lugs on the key engaging the face of the bar remote from the insulator, and cementitious material introduced into said recess subsequently to the insertion of the key thereinto and filling the remainder of the recess to permanently anchor the flanges and key therein.

85 6. In an insulator mounting, in combination, an insulator having a recess of rectangular cross-section in the end thereof, the walls of said recess inclined outwardly from the mouth to the bottom thereof, an insulator supporting bar against which the recessed end of the insulator rests, said bar having a

rectangular orifice therein registering with the recess in the insulator, flanges upstanding from opposite marginal edges of the orifice in the bar and extending into said recess in the insulator, a substantially U-shaped key, lugs extending from the extremities of the arms of the key, the key extending freely through the orifice in the bar and into the recess in the insulator and partially filling said recess, the aforesaid lugs on the key engaging the face of the bar remote from the insulator, and cementitious material introduced into said recess subsequently to the insertion of the key thereinto and filling the remainder of the recess to permanently anchor the flanges and key therein.

In witness whereof, I hereunto subscribe my name this second day of December, A. D. 1927.
